DESIGN.

F. K. WARD.
CHAIR.

No. 21,503.

Patented Apr. 26, 1892.

UNITED STATES PATENT OFFICE.

FRANK K. WARD, OF WASHINGTON, DISTRICT OF COLUMBIA.

DESIGN FOR A CHAIR.

SPECIFICATION forming part of Design No. 21,503, dated April 26, 1892.

Application filed March 30, 1892. Serial No. 427,129. Term of patent 14 years.

To all whom it may concern:

Be it known that I, FRANK K. WARD, a citizen of the United States, residing at Washington, in the District of Columbia, have invented and produced a new and Original Design for Chairs, of which the following is a specification.

This design has for its object to provide a novel and ornamental chair which comprises legs to stand stationary on the floor and presents to the eye a characteristic and distinguishing appearance.

The leading feature of the design resides in a chair having legs to rest on the floor, arm-posts rising from a seat-frame, and a pair of flat rectilinear chair-arms arranged, respectively, at opposite sides of the chair, projecting horizontally in front of the arm-posts, flaring outwardly apart, and formed with widened outer ends, which are uniformly curved into semicircular form and gradually decrease in width toward the chair-back.

The design is illustrated by the accompanying drawing, in which the figure is a perspective view of a chair embodying my design.

In the drawing the numerals 1 indicate the rear legs, which rise above a seat-frame 2 and are connected at the top by a panel 3, having upper and lower semicircular portions 4 and narrowed ends 5, which join the upper end portions of the rear legs. A transverse curved bar 6 is interposed between the rear legs in proximity to the seat-frame, and this transverse bar is connected with the top panel 3 through the medium of a series of rounds 7,

separated from each other. The front corners of the seat-frame are rounded, as at 8, and the front legs 9 have upper and lower circular portions separated by angular portions 10. The arm-posts 12 rise from the seat-frame and are curved outwardly, and the chair-arms 13 are flat and rectilinear on their upper surfaces. These chair-arms project horizontally in front of the arm-posts 12, flaring outwardly apart, and are formed with widened ends, which are uniformly curved into semicircular portions 14 and are gradually reduced in width on curved lines 15 toward the chair-back. The portions of the chair-arms which project horizontally in front of the arm-posts are provided with circular lines 16, surrounding bar-like portions 17, arranged flush with the upper surfaces of the chair-arms, and at the lower sides of the latter, under the circular lines and bar-like portions, are arranged pendent portions 18; but these lines and portions form no part of my design.

The design provides a chair which presents a handsome, characteristic, and distinguishing appearance to the eye.

What I claim is—

The design for a chair, substantially as shown and described.

In testimony whereof I have hereunto set my hand and affixed my seal in presence of two subscribing witnesses.

[L. S.] FRANK K. WARD.
